UNITED STATES PATENT OFFICE

2,559,456

RAILWAY TRUCK

William H. Meyer, St. Louis, Mo., assignor to
 General Steel Castings Corporation, Granite
 City, Ill., a corporation of Delaware

Application December 16, 1946, Serial No. 716,537

9 Claims. (Cl. 105—190)

1

The invention relates to railway rolling stock and more particularly to railway trucks in which the load supporting bolster is of the lateral motion type and is carried by springs supported by a spring plank carried by swing hangers suspended from the truck frame.

For good riding qualities in railway passenger cars, the flexibility of the truck bolster springs should be such that they provide soft spring action; and for good riding qualities, as well as safety at high speed, the springs at opposite sides of the truck should be spaced apart so that the least spring deflection is obtained under a given force tending to tilt the car body laterally, and such spring deflection or maximum stability of the car body against transverse tilting is obtained if the springs are spaced apart transversely of the truck as far as possible. When coil springs alone are used to support the bolster to obtain soft spring action, it is necessary to use a snubbing device or shock absorber to control the vertical action of the springs to prevent excessive rebound. When elliptic springs alone are used, they will be heavier, more expensive, more likely to take a permanent set, will require maintenance (lubrication of leaves) and, if soft action and maximum lateral stability is obtained, may be so long that it will be difficult to keep them within road clearance limits and to clear other truck parts.

The main object of the invention is to support the bolster by flexible spring units, each including both coil and elliptic springs, in which spring rebound is controlled without the use of snubbers or shock absorbers, the units being spaced apart transversely of the truck a maximum distance to obtain a high degree of bolster stability. The sliding contact between the leaves of the elliptic spring during the spring action produces sufficient friction between the leaves to snub the rebound. The snubbing action is determined by the load carried by the elliptic springs and by the total area of those portions of the surfaces of the leaves in sliding contact. The greater the load carried by the elliptic springs, the more pronounced is the snubbing action.

Longitudinally extending bolster anchors between the bolster and the truck frame steady the bolster against longitudinal movements relative to the truck frame to prevent pounding and sliding between the bolster and the frame transoms which would interfere with free vertical movement of the bolster. With this arrangement, there is provided controlled soft spring action and easy riding qualities in the truck, and chafing

2

plates, shock absorbers and like equipment are unnecessary.

Other objects will be apparent to those skilled in the art from the following description and accompanying drawings in which:

Figure 1 is a top view showing a longitudinal half of a railway truck embodying one form of the invention.

Figure 2 is a side elevation thereof.

Figure 3 is a detail transverse vertical section taken approximately on line 3—3 of Figure 1 and drawn to enlarged scale.

Figures 4, 5 and 6 are views similar to Figures 1, 2 and 3, respectively, and show another form of the invention, Figure 6 being a detail transverse vertical section taken approximately on the line 6—6 of Figure 4 and drawn to enlarged scale.

Figures 7, 8 and 9 are views similar to Figures 1, 2 and 3, respectively, and show still another form of the invention, Figure 9 being a detail transverse vertical section taken approximately on the line 9—9 of Figure 7 and drawn to enlarged scale.

The railway truck illustrated in Figures 1, 2 and 3 comprises the usual wheel and axle assemblies 1, journal boxes 2, longitudinal equalizers 3 carried on the boxes, equalizer springs 4, and truck frame 5 preferably consisting of a one-piece casting including transversely spaced truck sumps 6 and wheel pieces 7 with depending pedestal legs 8 receiving journal boxes 2 between them. The truck is of the lateral motion bolster type and has pairs of swing hangers 9 at opposite sides of the truck pivotally suspended by pins 10

from brackets 1a extending outwardly from wheel pieces 7. Each pair of hangers 9 carries a cross bar 11 mounting a bearing 12 which supports the adjacent end of a spring plank 13. Near the ends of spring plank 13 are mounted yielding pads 14

40 comprising alternate layers of rubber 15 and steel 16 bonded together. Pads 14 support spring seat members 17 to provide limited lateral movement of the seat members relative to the spring plank. Yielding pads 14 are adapted to absorb small lateral shocks and to damp lateral shocks of larger magnitude as described in the copending application of Harry M. Pflager, Serial No. 671,559, filed May 22, 1946, now U. S. Patent No. 2,538,380, dated January 16, 1951.

50 A spring unit 18 is mounted on spring seat member 17 and supports the adjacent end of a bolster 21 having a center plate 22 on which is mounted a vehicle body (not shown). Each spring unit includes a pair of longitudinally spaced coil springs 19 and three elliptic springs

20 extending between the coil springs transversely of the truck. Coil springs 19 are seated on spring seat member 17 outwardly of the truck beyond the corresponding truck frame wheel piece 7 and equalizer 3. Transversely extending elliptic springs 20 are seated on a raised portion 23 of spring seat member 17 above equalizer 3 and below truck frame wheel piece 7. The center of the spring unit lies in a vertical line positioned longitudinally of the truck approximately midway between the axes of the coil springs and positioned laterally of the truck approximately midway between a longitudinally extending vertical plane passing through the axes of the coil springs and a plane parallel thereto passing through the axes of the elliptic springs. With this arrangement, the center *x* (Figure 1) of the spring unit is located outwardly of the truck beyond the corresponding truck frame wheel piece and equalizer to provide maximum stability of the car body against transverse tilting. The center *x* of the spring unit is located transversely of the truck as far as possible without having the outer ends of the elliptic springs extend beyond the road clearance line when the bolster swings laterally.

A longitudinally extending bolster anchor 24 at each side of the truck is attached at one end to the adjacent end of bolster 21 and at the other end to a bracket 25 rigid with and extending outwardly of truck frame wheel piece 7. The bolster anchors steady the bolster against longitudinal movements relative to the truck frame to prevent undue slapping or vibrating noises or resistance to free vertical movement of the bolster as described above.

In the embodiment shown in Figures 4, 5 and 6, pairs of swing hangers 109 are pivotally suspended at opposite sides of the truck from brackets 107a extending outwardly from wheel pieces 107. Each pair of hangers carries a cross bar 111 upon which is mounted a bearing 112 supporting a seat member 112a inclined to the horizontal and mounting a yieldable pad 114 of alternate layers of rubber 115 and steel 116 bonded together. The pad supports the downwardly inclined end of a spring plank 113 as shown and described in copending application of Edmund S. Beckette and James C. Travilla, Jr., Serial No. 668,506, filed May 9, 1946.

The pad mounting of the spring plank absorbs the shocks due to small track irregularities without corresponding lateral movement of the car body or the application of undesirable shocks thereto.

Spring unit 118 is mounted near the end of spring plank 113 and comprises a pair of coil springs 119, positioned side by side longitudinally of the truck and outwardly of the truck beyond the corresponding frame wheel piece 107 and equalizer 103, and an elliptic spring 120 positioned outwardly of the coil springs and extending longitudinally of the truck. The spring unit supports the adjacent end of a bolster 121. In this embodiment, both the coil springs and the elliptic spring are positioned outwardly of the truck beyond frame wheel piece 107 and equalizer 103 and the center *y* (Figure 4) of the spring unit also is located outwardly of the truck beyond frame wheel piece 107 and equalizer 103.

At each side of the truck, a longitudinally extending bolster anchor 124 between the bolster and the truck frame steadies the bolster against longitudinal movement relative to the truck frame. One end of anchor 124 is connected to an outwardly extending projection 107b on one

of the brackets 107a and the other end is connected to a bracket 121a on the end portion of bolster 121.

In the embodiment shown in Figures 7, 8 and 9, pairs of swing hangers 209 are suspended at opposite sides of the truck from the outer side of frame wheel piece 207 by pins 210. Each pair of hangers carries a cross bar 211 on which is mounted a bearing 202 supporting a spring plank 213. A spring unit 218 is mounted near the end of the spring plank and supports the adjacent end of a bolster 221. The spring unit comprises a pair of coil springs 219, positioned side by side longitudinally of the truck and outwardly of the truck beyond the corresponding truck frame wheel piece 207 and equalizer 203, and a longitudinally extending elliptic spring 220, positioned inwardly of and adjacent the coil springs and above equalizer 203 and below truck frame wheel piece 207. The center *z* (Figure 7) of the spring unit is located outwardly of the truck beyond frame wheel piece 207 and equalizer 203 as in the embodiments previously described. Longitudinally extending bolster anchors 224 between the bolster and the truck frame steady the bolster against longitudinal movement relative to the truck frame.

In all the embodiments described, the bolster is supported near its ends by a highly flexible spring unit in which the spring rebound is controlled by the elliptic springs without the use of snubbers or shock absorbers. Snubbing action is determined by the load carried by the elliptic springs and by the total area of those portions of the surfaces of the leaves in sliding contact. The greater the load carried by the elliptic springs, the more pronounced the snubbing action. The bolster anchors between the bolster and truck frame prevent the bolster from moving longitudinally relative to the truck frame sufficiently to strike the truck frame transoms and interfere with the free vertical action of the bolster.

The details of the construction may be varied without departing from the spirit of the invention, and the exclusive use of those modifications coming within the scope of the claims is contemplated.

What is claimed is:

1. In a railway truck including wheel and axle and journal box assemblies, longitudinally extending equalizers supported thereon, a truck frame spring-supported from said equalizers, swing hangers pivotally suspended from said frame, and a spring plank supported from said hangers, bolster supporting spring units each including coil springs and an elliptic spring, said spring units being positioned near the ends of and being supported by said spring plank, said coil springs in each unit being spaced longitudinally of the truck and being located outwardly of the truck beyond the corresponding equalizer, and said elliptic spring in each unit extending transversely of the truck between said coil springs with its seat positioned inwardly of the truck relative to the coil springs, the center of each spring unit being spaced from the longitudinal center line of the truck at least as far as the associated equalizer, and a bolster yieldingly supported by said spring units.
2. In a railway truck including wheeled axle and journal box assemblies, longitudinally extending equalizers supported thereon, a truck frame spring-supported from said equalizers, swing hangers pivotally suspended from said

frame, and a spring plank supported from said hangers; bolster supporting spring units each including coil springs and an elliptic spring, said spring units being positioned near the end of and being supported by said spring plank, said coil springs in each unit being positioned side by side longitudinally of the truck and being located outwardly of the truck beyond the corresponding equalizer, and said elliptic spring in each unit extending longitudinally of the truck and being positioned outwardly of the truck beyond said coil springs with its seat so positioned that the center of each spring unit is spaced from the longitudinal center line of the truck at least as far as the associated equalizer, and a bolster yieldingly supported by said spring units.

3. In a railway truck including wheeled axle and journal box assemblies, longitudinally extending equalizers supported thereon, a truck frame spring-supported from said equalizers, swing hangers pivotally suspended from said frame, and a spring plank supported from said hangers; bolster supporting spring units each including coil springs and an elliptic spring, said spring units being positioned near the ends of and being supported by said spring plank, said coil springs in each unit being positioned side by side longitudinally of the truck and being located outwardly of the truck beyond the corresponding equalizer, and said elliptic spring in each unit extending longitudinally of the truck and being positioned inwardly of the truck from said coil springs with its seat so positioned that the center of each spring unit is spaced from the longitudinal center line of the truck at least as far as the associated equalizer, and a bolster yieldingly supported by said spring units.

4. In a railway truck, wheel and axle assemblies, journal boxes on said assemblies positioned outwardly of the wheels, equalizers between journal boxes at the same side of the truck, a truck frame having wheel pieces supported from the equalizers and positioned outwardly of the wheels, pairs of swing hangers pivotally suspended from the outer sides of the wheel pieces, a spring plank supported from the hangers, a bolster-supporting spring unit at each end of the spring plank positioned between the corresponding swing hangers, each spring unit comprising leaf and coil springs with their respective seats spaced apart a substantial distance transversely of the truck and positioned at least as far from the longitudinal center line of the truck as the corresponding equalizer.

5. A truck as described in claim 4 which includes a flat rubber pad between said seats and the spring plank and adapted to yield in shear under lateral forces applied to the structure and insufficient to swing said hangers on their pivots.

6. A railway truck as described in claim 4 which includes an anchor device extending longitudinally of the truck with connections at its ends to the bolster and truck frame respectively to steady the bolster against movement longitudinally of the truck relative to the truck frame, said connections accommodating movement of the bolster laterally and vertically relative to the truck frame.

7. In a railway truck, wheel and axle assemblies, journal boxes on said assemblies positioned outwardly of the wheels, equalizers between journal boxes at the same side of the truck, a truck frame having wheel pieces supported from said equalizers, swing hangers pivotally suspended

from the outer sides of said wheel pieces, a spring plank supported from said hangers, a bolster-supporting spring unit at each side of the truck, each spring unit with its center at least as far from the longitudinal center line of the truck as the corresponding equalizer, each unit including a coil spring assembly and an elliptic spring assembly, each spring assembly having an individual seat on the spring plank positioned different distances from and at least as far from said center line as the corresponding equalizer.

8. In a railway truck, wheel and axle assemblies, journal boxes on said assemblies positioned outwardly of the wheels, equalizers between journal boxes at the same side of the truck, a truck frame having wheel pieces supported from said equalizers, swing hangers pivotally suspended from the outer sides of said wheel pieces, a spring plank supported from said hangers, a bolster-supporting spring unit at each side of the truck, each spring unit including a coil spring assembly and an elliptic spring assembly, one spring assembly having a seat on the spring plank positioned at least as far from the longitudinal center line of the truck as the corresponding equalizer, and the associated spring assembly having a seat on the spring plank positioned a substantially greater distance from said center line than the first mentioned seat.

9. In a railway truck, wheel and axle assemblies, journal boxes on said assemblies positioned outwardly of the wheels, equalizers between journal boxes at the same side of the truck, a truck frame having wheel pieces supported from said equalizers, swing hangers pivotally suspended from the outer sides of said wheel pieces, a spring plank supported from said hangers, a bolster-supporting spring unit at each side of the truck, each spring unit including a coil spring assembly and an elliptic spring assembly, the elliptic spring assembly having a seat on said spring plank positioned at least as far from the longitudinal center line of the truck as the corresponding equalizer, and the associated coil spring assembly being seated on said spring plank a greater distance from said center line than said leaf spring assembly seat.
